CARPET NEEDLE

Filed Sept. 9, 1927

Emil J. Seeber
INVENTOR
BY Victor J. Evans
ATTORNEY

UNITED STATES PATENT OFFICE

EMIL J. SEEBER, OF CHICAGO, ILLINOIS

CARPET NEEDLE

Application filed September 9, 1927. Serial No. 218,531.

This invention relates to certain novel improvements in carpet needles and is particularly directed to improvements in a mechanism which is adapted for the insertion of the weft.

It is among the objects of my invention to provide a device of the just named character which will be simple in construction and economical to manufacture.

10 An object, ancillary to the foregoing, is to provide such a device that may be formed of metal, and preferably by a stamping operation.

Another object of the invention is to form 15 the device in such a way that the operation thereof will be greatly facilitated due to the advantageous handle formation.

Other objects will appear hereinafter.

The invention consists in the novel combination and arrangement of parts to be hereinafter described and claimed.

The invention will be best understood by reference to the accompanying drawings, showing the preferred form of construction 25 and in which:

Fig. 1 is a side elevational view of the device, certain parts having been broken away;

Fig. 2 is a sectional view taken substantially on the line 2—2 of Fig. 1; and

30 Fig. 3 is a detail view taken substantially on the line 3—3 of Fig. 1.

Carpet needles of the type herein disclosed are adapted for the insertion of the weft between the warp threads in a manner well understood in the art. In my preferred form of construction as disclosed in the accompanying drawings, I provide two members which are secured together for relative reciprocity. One of these members carries the 35 needle and the other carries the looper, these terms being specifically defined hereinafter.

The needle 10 is formed substantially U-shaped as shown best in Fig. 3 and includes a pointed end 11. An eye is formed in the needle 10 near the pointed end 11 thereof through which the weft is inserted during operation of the needle. In operation, the needle carrying the weft thread is inserted between two threads of the warp. In order 45 to retain the weft in this inserted position a

so-called looper is then inserted between the same two warp threads, said looper engaging the weft and retaining it in position as the needle is withdrawn. Then the needle is moved over so as to be in position to be inserted between the next succeeding warp threads between which it is then inserted. The looper is then withdrawn from the first position and is inserted beside the needle. 55 This action is continued until all of the warp threads have been traversed. In order to facilitate this action the needle and looper are mounted on relatively reciprocal members. 60

The needle 10 is secured, by any suitable medium, such as the rivets 13, to the needle member 14. The looper 15 is secured, as by rivets 16, to the looper member 17. As stated, the needle 10 is substantially U-shaped. The looper 15 is reciprocally mounted in the U-portion of the needle so as to be properly guided. 65

The members 14 and 17 include co-extensive portions 18 and 19, respectively. In the portion 18 of the needle member 14 a slot 20 is formed. A rivet 21 is secured to the portion 19 of the looper member 17 and extends through the slot 20. The rivet 21 has a headed end 22 which serves to hold members 14 and 17 in slidable relation, in such a manner as to provide a certain amount of relative side movement therebetween. The portion 19 of the looper member 17 has a slot 23 formed therein and the rivet 24 carried by the portion 18 extends therethrough and has a headed end 25 which also acts to hold the members 14 and 17 in slidable relation. 75

The parts as illustrated in Fig. 1 are in position such that the needle 10 is ready to be inserted. After the needle 10 has been inserted, in the manner described, the looper 15 is moved forwardly. This action is permitted since the rivets 21 and 24 are at substantially the mid-point of the extent of the slots 20 and 23. After the looper 15 is moved forwardly the needle 10 is retracted and reinserted and then the looper 15 is retracted and re-inserted, substantially as described. 85 In order to facilitate this relative reciprocity 90

95

100

cation of the members 14 and 17 a suitable handle structure is provided.

As depicted, the portion 18 has an offset portion 26 in the region of the section to which the needle 10 is secured. This offset portion is provided in order that the needle 10 and looper 15 may be properly mounted. Formed unitarily with the offset portion 26 is a portion 27 which is bent rearwardly so as to be coextensive for a predetermined distance with the portion 18 but in spaced relation thereto, thus being substantially U-shaped in form. At the upper end of the portion 18 an extension 28 thereof is provided which is substantially S-shaped and which includes a portion 29 disposed so as to be coextensive with, for a short distance, but spaced from the portion 18. The portion 28 terminates in a portion 30 that extends parallel to and which is juxtaposed to the upper end of the portion 27. The ends of portions 30 and 27 terminate at the same point so as to provide a tang portion and the handle 31 is secured thereto.

The portion 19 has a portion 27' at its lower end which is disposed and formed similarly to the portion 27. The portion 19 also includes an S-shaped portion 28' which has an end portion 30' arranged similarly to the portion 30. The handle 31' is secured to the ends of the portions 30' and 27' in the same manner as the handle 31 is secured to the ends of portions 27 and 30.

By grasping the handles 31 and 31' and allowing the index fingers to lie on the portions 27 and 27' an operative may very expeditiously employ the needle structure. Since certain of the fingers will be disposed between the portions 29 and 29' and the handles 31 and 31' and because of the provision for the index fingers the needle structure may be firmly held and therefore very accurately guided.

It is apparent that the structure is very simple and may be formed of metal in a very expeditious manner.

If desired, the portions 27 and 27' may be omitted and the portions 28 and 28' may be disposed at right angles to the portions 18 and 19 and the handles 31 and 31' would then be secured to these portions 28 and 28'. However, I have found the previously described structure to be very advantageous and it is the preferred form.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what

I claim as new and desire to protect by Letters Patent is:

1. A device of the class described including a needle member carrying a needle at the forward end thereof, a looper member carrying a looper at the forward end thereof adapted to cooperate with said needle, said needle member and said looper member embodying co-extensive portions adapted to be slidably secured together, said members including portions adapted to cooperate with said co-extensive portions to form substantially U-shaped portions with the bight portion thereof arranged adjacent said needle and looper, said co-extensive portions having substantially S-shaped portions at the opposite ends from said bight sections, said S-shaped portions including portions adapted to cooperate with the cooperating portions of said U-shaped portions to form tang elements, and handles secured to said tang elements.

2. A device of the class described including a needle member carrying a needle at the forward end thereof, a looper member carrying a looper at the forward end thereof adapted to cooperate with said needle, said needle member and said looper member embodying co-extensive portions, means for slidably connecting said co-extensive portions for reciprocation relative to each other, said members including portions extending away from the point of connection of said members with said needle and said looper to form said members into substantially U-shape, and portions extending from the ends of said co-extensive portions adapted to cooperate with the ends of said portions defining said U-shape to provide tang elements, and handle members connected to said tang elements.

3. A device of the class described including substantially U-shaped needle and looper members, said members including co-extensive portions, means for connecting said co-extensive portions for relative reciprocation, the co-extensive portion of said needle member having a portion adjacent the bight portion of said needle member offset in a direction away from the co-extensive portion of said looper member, a needle connected in said offset portion and extending beyond said bight portion, a looper secured to said looper member on the co-extensive portion thereof adjacent the bight portion, said looper member being adapted to cooperate with said needle member, said co-extensive portions having portions at the free end thereof adapted to extend toward the other branches of said U-shaped members to provide tang elements, and handle members connected to said tang elements.

In testimony whereof I affix my signature.
EMIL J. SEEBER.
